FIG. 3

FIG. 7

FIG. 5

FIG. 4

FIG. 6

FIG. 1 is an exploded perspective view of a combined bottle and closure therefor showing my new design;

FIG. 2 is an elevation of the bottle and closure combined;

FIG. 3 is an elevation of the bottle alone;

FIG. 4 is a top plan view of the bottle of FIG. 3;

FIG. 5 is a sectional elevation of the closure alone;

FIG. 6 is a top plan view of the closure of FIG. 5; and

FIG. 7 is a bottom plan view of the closure of FIG. 5.

The side opposite that shown is substantially similar in appearance to the side shown. The bottom is plain and unornamented.

I claim:

The ornamental design for a combined bottle and closure therefor, as shown and described.
